BRUCE V. EDWARDS, OF NEWARK, NEW JERSEY, ASSIGNOR TO PATERSON PARCHMENT PAPER COMPANY, OF PASSAIC, NEW JERSEY, A CORPORATION OF NEW JERSEY.

SHREDDING MECHANISM.

1,178,386.

Specification of Letters Patent.

Patented Apr. 4, 1916.

Application filed December 10, 1912, Serial No. 735,967. Renewed October 11, 1915. Serial No. 55,352.

To all whom it may concern:

Be it known that I, BRUCE V. EDWARDS, of the city of Newark, county of Essex, State of New Jersey, a citizen of the United States, have invented a new and useful Shredding Mechanism, of which the following is a specification.

My invention relates to machines of the kind commonly used for slitting, shredding, or cutting sheet material such as paper, cardboard, leather, wood, fabrics, and the like, and, more particularly it relates to that class of machines in which a plurality of rotatable cutting edges is used.

In machines of this kind,—producing packing material, shredded products, ribbon and other forms of confetti, and the like,—it has been found in practice to be a matter of very considerable difficulty to so handle the product as to prevent its being carried back into the machine, with the result that the cutters become clogged and the mechanism has to be stopped to disengage the cuttings.

The essentials of my invention consist in providing, in a mechanism of this class, and in combination with opposing and coöperating series of rotatable cutters, novel means for automatically removing the product from the cutter edges, and guiding it away therefrom.

One of the preferred forms of my invention is shown in the accompanying drawings, in the form of a machine for slitting or shredding paper stock into packing material. It is manifest, however, that my invention may be applied in many forms, and that it may be widely varied by the skilled designer and mechanic without departing from the essentials thereof, and I desire it to be understood that I claim it in any and all of the equivalent mechanical forms in which it may be produced.

Referring to the drawings:—Figure 1 represents a view in sectional elevation through a portion of the machine, and Fig. 2 represents a sectional plan taken on the line 2—2 of Fig. 1 looking in the direction indicated by the arrow. Fig. 3 represents a side view of one of the cutter-clearing and product-guiding members.

In the drawing the numerals 1 and 2 represent, respectively, shafts upon which the opposing series of circular cutters 3 and 4 are mounted for rotation. These shafts are

preferably connected together by gearing for coincident rotation, the shafts and their driving mechanism being mounted upon the machine frame (not shown) in any desired or suitable manner.

The cutters 3 and 4 may be secured to their respective actuating shafts in any desired manner; I preferably fasten them by means of the keys 5 and 6, mounted in the keyways 7 and 8 in the shafts and engaging corresponding recesses in the cutters.

A series of spacing collars 9 and 10 is similarly mounted upon each shaft between the cutters, and each series of cutters is so located with reference to the other as to stand opposite to the space collars of the opposing series. In this position the cutting edges may be adjusted to overlap any desired extent.

The cutter-clearing and product-guiding devices in this mechanism take the form of the members 11 and 12, mounted in like plurality between the cutters 3 and 4 of each series, and preferably encircling the space collars 9 and 10. Independent supporting and locating devices are provided for these members, in the rods 13 and 14 extending throughout the machine parallel to the shafts 1 and 2, these rods being secured to the machine frame in any desired manner. Suitably-formed extensions 15 and 16 on the members 11 and 12 engage the rods 13 and 14.

The material to be cut is delivered from above by and between the conveyer belts 17 and 18,—its path being indicated by the stream of arrows,—between and past the cutters 3 and 4, by which it is slit into narrow, continuous ribbons of the desired width and in length corresponding to the stock delivered to the machine.

At the points indicated by the numerals 19 and 20 I so form the opposed and adjacent edge portions of the members 11 and 12 as to lie within the peripheral edges of the cutters between which they are mounted, from these points the edge portions are carried gradually outwardly to the points 21 and 22 where they overlap the peripheral edges of the cutters.

As the material is fed to the machine and cut, the product which adheres to the cutting edges of the cutters is carried thereby from the point indicated by the numeral 23, through the spaces between the cutters and

the opposing edges of the members 11 and 12, to the point where it encounters the overlapping edge portions 21 and 22 of the members 11 and 12 and is disengaged from 5 or wiped off from the the cutting edges, forming itself into irregular spherical masses 24, 24.

I preferably make the members 11 and 12 slightly thinner than the adjacent space 10 collars 9 and 10 about which they are mounted, so as to eliminate unnecessary friction.

I also preferably construct the cutting members with their associated parts in sections of definite length, so that as many of 15 these sections as are desired may be assembled and mounted upon a suitably formed frame, in conjunction with appropriate driving mechanism.

Having thus described my invention I 20 claim:—

1. In a machine of the kind described the combination with opposed series of rotatable cutters, alternated and overlapping at the cutting point, of opposed series of non- 25 rotatable cutter wipers, similarly alternated and formed eccentrically to remove adhering matter continuously from the cutting edges of all the cutters.

2. In a machine of the kind described the combination with opposed series of rotatable cutters, alternated and overlapping at the cutting point, of non-rotatable and eccentrically-formed cutter wipers, similarly 30 opposed and alternating, to remove adhering matter from the cutting edges of all the 35 cutters.

3. In a machine of the kind described the combination with opposed series of rotatable cutters, alternated and overlapping at the cutting point, of non-rotatable eccentrically-formed cutter wipers mounted 40 between each cutter in each series, and similarly opposed and alternated, to remove adhering matter from the cutting edges of all 45 the cutters.

4. In a machine of the kind described a

non-rotatable cutter wiping member adapted to be mounted about a rotatable shaft in a relatively fixed position thereto, with means to retain said member in said relative 50 position.

5. In a machine of the kind described the combination of opposing series of rotatable cutters, mounted upon shafts common to each series of cutters, with a like series of 55 non-rotatable cutter wiping members mounted between each cutter in each series, upon the common shafts whereby said cutters are driven, and means to retain said wiping members in relatively fixed positions while 60 said shafts are rotating.

6. In a machine of the kind described the combination of opposed series of rotatable cutters, like opposed series of non-rotatable cutter-wiping members arranged to preserve 65 a relatively-fixed position while the cutters revolve, each of the opposed series of cutters and cutter-wiping members being mounted upon or about the same shaft.

7. In a machine of the class described the 70 combination with the frame, of a rotatable shaft, a cutter and a space collar mounted upon said shaft, a non-rotatable cutter wiping member encircling said space collar and having a projecting lug to engage a retaining rod whereby the cutter wiper is prevented 75 from rotating and is maintained in a fixed position with relation to the rotating cutter and space collar, and the said retaining rod.

8. A cutter wiping member adapted to encircle a retaining shaft, said member having an extension to engage an independent retaining device, and being formed circumferentially as, and for the purpose, specified. 85

In testimony whereof I hereunto set my hand this second day of December, 1912, in the presence of two attesting witnesses.

BRUCE V. EDWARDS.
